US00D550033S

(12) **United States Design Patent** (10) **Patent No.:** **US D550,033 S**
Bodum (45) **Date of Patent:** **** Sep. 4, 2007**

(54) **DRINKING GLASS**

(75) Inventor: **Jørgen Bodum**, St. Niklausen (CH)

(73) Assignee: **Pi-Design AG**, Triengen (CH)

(**) Term: **14 Years**

(21) Appl. No.: **29/244,213**

(22) Filed: **Dec. 7, 2005**

(30) **Foreign Application Priority Data**

Jun. 7, 2005 (DK) ..... DA 2005 00166

(51) **LOC (8) Cl.** **07-01**

(52) **U.S. Cl.** **D7/509; D7/523**

(58) **Field of Classification Search** D7/509-11, D7/522-24, 528, 529, 531-533, 536, 537, D7/540, 542; D9/558, 575; D11/140, 143, D11/145, 146, 152, 153; 215/DIG. 7; 220/568, 220/574, 608, 623, 658, 659, 662, 669, 592.17
